GLUING MACHINE

Julius M. Minkow, New York, N. Y., assignor to
Robert Minkow, New York, N. Y.

Application November 22, 1934, Serial No. 754,294

4 Claims. (Cl. 91—51)

This invention relates to a gluing machine and has for its primary object to provide, in a manner as hereinafter set forth, a machine of the class referred to so constructed and arranged to enable convenient access to the glue applying and material pick-up elements whereby they may be expeditiously and thoroughly cleaned when occasion requires.

A further object of the invention is to provide, in a manner as hereinafter set forth, a machine of the class referred to capable of efficiently applying an adhesive or other coating to canvas, buckram, leatherette, vellum, cardboard, sheets of paper, etc., whether thin, thick, smooth, embossed or pebbled.

Further objects of the invention are to provide, in a manner as hereinafter set forth, a machine of the class referred to which is simple in its construction and arrangement, strong, durable, compact, conveniently operated, readily repaired when occasion requires, thoroughly efficient in its use, expeditiously cleaned, and comparatively inexpensive to manufacture.

To the above ends essentially, and to others which may hereinafter appear, the invention consists of such parts and such combination of parts which fall within the scope of the invention as claimed.

In the drawings:

Figure 1 is a side elevation of the machine,
Figure 2 is a longitudinal sectional view with the movable section of the machine supported vertically to enable convenient access to be had to the glue applying and material pick-up elements when the said elements are to be cleaned,

Figure 3 is a longitudinal sectional view of the machine when in position for gluing and

Figure 4 is a top plan view of the stationary section of the machine.

The machine includes a stationary section 5 and a movable section 6 which is hinged to section 5. The latter is to be mounted upon a support 7 to which is fixed an electrical motor 3 provided with a driving connection 9 for a purpose to be referred to. A power circuit 10 for motor 3 is connected to support 6 and has interposed therein a cut-out 11.

The section 5 includes a rectangular trough 12 formed of an outwardly inclined front wall 13, a rearwardly inclined rear wall 14, a pair of vertically disposed side walls 15, 16, a bottom 17 and a normally closed drain 18. The trough 12 has a series of spaced supporting legs 19 depending from bottom 17. The trough 12 is of the depth, length and width desired and may be employed

for containing a body 20 of hot or cold glue, fluid paste, gum, silicate of soda, paraffine, or other suitable coating material, and it is to be understood that the term glue is to mean any material which may be used by the machine for application to leatherette, vellum, canvas, buckram, cardboard, sheets of paper, etc., whether thin, thick, smooth, embossed or pebbled.

The side walls 15, 16 have their rear portions 21 of less height than the remaining portions 10 thereof and they are also formed with aligning rectangular cutouts 22 and aligning semi-oval shaped cutouts 23. The cutouts 22 are arranged forwardly of cutouts 23. The cutouts 22, 23 open at the top edges of the high portions of the side 15 walls. The purpose of the cutouts will be hereinafter referred to. The trough has its front and rear walls of greater thickness than its side walls. The trough has its front and rear walls arranged between and flush with its side walls. 20 The front wall of the trough is of greater height than its rear wall. Arranged within and extending above the side walls of the trough is a pair of spaced vertically disposed parallel supports 24 having enlarged annular heads 24'. The 25 trough, legs and supports 24 are formed from a single casting.

Integral with the top edge of the rear wall 14 at the ends thereof is a pair of vertically disposed apertured lugs 25, 26 opposing the inner faces of 30 the depending integral apertured parts 27, 28 at the rear ends of a pair of supports 29, 30 respectively which normally seat upon the side walls of the trough and close the cutouts 22 and 23. The apertures in said lugs align with the apertures in 35 said parts 27, 28. The supports 29, 30 at their rear ends are pivotally connected as at 31, 32 respectively to the lugs 25, 26 respectively. The pivots extend through the aligning apertures of the lugs and parts 27, 28. Positioned upon the 40 top edge of the rear wall 14 and extending rearwardly therefrom at an upward inclination are holders 35, 36 for a purpose to be referred to. The holders are fixed stationary to the rear wall 45 of the trough 12 by the anchoring means 37, 38. The holders form parts of the stationary section 5. The supports 29, 30 form parts of the shiftable section 6.

The section 5 also includes a wiper roll 39 disposed transversely of the trough 12. The roll 39 50 is mounted on a shaft 40 which extends through bearings 41 at the rear ends of a pair of adjustable spring controlled positioning devices 42 for the wiper roll 39. The devices 42 are slidably mounted at their front ends in the heads 24' of 55

the supports 24. Each of said devices 42 includes a combined stop and adjusting nut 43 at its front end. The shaft 40 is mounted in the cutouts 22. The shaft 40 projects from side wall 16 of the trough and has fixed thereto a gear wheel 45. The devices 42 resiliently maintain the wiper roll 39 at a point substantially centrally of the front of and against the periphery of a glue applying roll 46 which is of materially greater diameter than roll 39. The said devices 42 act as a safety means in case a foreign solid material is in the glue and comes up between the rolls 39, 46. The roll 46 is carried by a shaft 47 which is journaled in the cutouts 23 and projects from the side wall 16 of the trough. The shaft 47 has fixed thereto a gear 48 and a pinion 49. The latter meshes with and drives gear 45. Anchored to the side wall 16 of the trough is a bearing 50 in which is journalled a stub shaft 51 carrying a pinion 52, and a pulley 53. The pinion 52 meshes with and drives the gear 48. The pulley 53 is operated from the driving connection 9 which leads from motor 8.

The section 6 not only includes the supports 29, 38 but also a pair of superposed guide rolls 54, 55, 25 a combined material holding and guide roll 56 above and rearwardly of roll 55, a series of spaced parallel pick-up or pick-off fingers 57, a pair of connecting rods 58, 59, a holding bar 60 for the fingers 57, a carrier 61 for the fingers 57, a platform or table 62 for the material which is to be operated upon, a pair of spring controlled latching members 63 for the supports 29, 38, pivots 64 for the members 63, aligning inclined cutouts 64', aligning vertical cutouts 65, aligning vertical cutouts 66, and a pair of adjustable closures 67, each common to a cutout 65 and 66.

The supports 29, 30 consist of forward parts 68, intermediate parts 69 of greater height than parts 68 and rear parts 70 of greater height than parts 40 69. The cutouts 64, 65 open at the top edges of the parts 69. The cutouts 66 open at the top edges of parts 70. The closures 67 are mounted on the top edges of parts 69 and are adjustably connected to the latter by the retaining screws 71 45 having large heads. The rolls 54, 55 and 56 are carried by the shafts 72, 73, and 74 respectively. When the machine is in active position, the roll 54 is arranged over roll 39 and positioned in proximity but spaced from the front of roll 46; the roll 55 is arranged over and extends rearwardly from the roll 54; the roll 55 is disposed in spaced relation to the upper portion of the front of roll 46; the roll 56 is arranged above and rearwardly of roll 55 and in spaced relation to the latter; and 55 the roll 56 is positioned over and slightly forward of the vertical median of roll 46, as well as being spaced from the latter. The shafts 72, 73 extend into the inclined cutouts 64. The shaft 74 is seated in the cutouts 65. The pick-up fingers 57 are arranged over roll 46 rearwardly of and in proximity to the guide roll 56.

The pick-up fingers are of like form and each consists of a plate 75 gradually increasing in width from rear to front. The forward end 76 of plate 75 inclines rearwardly from its lower to its upper end. The bottom edge 77 of plate 75 inclines downwardly from rear to front. The plate 75, in proximity to its rear end, is formed with an opening 78 and between its vertical median and forward end is provided with an opening 79 arranged below opening 78. The side marginal portions of the plate 75 bordering the end 76 are oppositely beveled, as at 80, to form a feathered edge at the forward end of the plate. 75 The holding bar 60 extends through the open-

ings 79 in the fingers 57. The bar 60 functions to hold the pick-up or pick-off fingers down in case glue collects on the ends of the fingers.

The carrier 61 is in the form of an elongated bar extending through the openings 78 in the fingers 57. These latter are fixed to the carrier. The carrier 61 is provided at its ends with clamping nuts 64. The carrier 61 is extended through the cutouts 66 in the supports 29, 30 and the nuts 64 about the outer side faces of said supports. 10

The connecting rod 58 is anchored to the forward ends of the parts 68 of the supports 29, 30. The connecting rod 59 is anchored to the rear parts 70 of the supports 29, 30. The platform or table 62 is positioned upon the top edges of the parts 68 and abuts the lower end of the front edges of the parts 69 of the supports 29, 30. The platform 62 is of a length to project forwardly a substantial distance beyond the front of the trough 12. The width of platform 62 is such as to have 20 its sides arranged over the sides of trough 12. The platform 62 is provided with spaced legs 62 for seating upon the top edge of the front wall 13 of trough 12. The platform 62 is detachably secured upon the parts 68 by set screws 33. 25

Arranged at the front of the trough 12 and leading to motor 8 is a controlling means 84 for the latter.

The outer faces of the sides 15, 16 of trough 12 are formed with lugs 65 coacting with the latching members 63 for detachably securing the section 6 relative to section 5 in the position shown in Figures 1 and 3. The controlling springs for members 63 are designated 86. The pivots 64 are secured in the parts 68 of supports 35 29, 30 rearwardly of and in proximity to rod 58. The latching members 63 extend above said parts 68 to be in convenient reach of the attendant.

The material which is to be acted upon is indicated at 87. The material is extended between 40 guide rolls 54, 55, picked up and glue applied to one face of the material by roll 46. The roll 56 causes the material to pass towards the pick-up fingers 57 and these latter function to direct the coated material in the manner as shown in Figure 45 3.

When it is desired to clean roller 46, as well as rollers 54, 55, and 56 and the fingers 57, the section 6 is released and swung to the full line position shown in Figure 2. Section 6 is maintained 50 in such position by the rod or bar 59 seating upon the holders 37, 38. By this arrangement convenient access may be had to those elements of the machine which are to be cleaned.

What I claim is:

1. In a gluing machine, a glue containing trough, a glue applying roll within and supported by the trough, a wiping roll within and supported by the trough and arranged relatively to the front of said other roll, driven operating means for said 60 rolls, a pair of superposed guide rolls arranged at the front of the applying roll and above the wiping roll, a platform positioned over the trough forwardly of said applying roll, a combined holding-down and guide roll arranged over the top 65 of the applying roll and rearwardly of said superposed rolls, a set of spaced pick-up fingers arranged over the top of the applying roll and rearwardly of and extending in close proximity to the bottom of the rear side of said combined holding-down and guide roll, shiftable supporting means common to and for bodily shifting simultaneously said platform, guide rolls and pick-up fingers to a position rearwardly of said applying roll, said shiftable supporting means being normally seated 70 75

directly upon the sides of and hinged at its rear end to the rear end of the trough, and spaced parallel holders extending rearwardly from said trough for maintaining said supporting means upright when in shifted position.

2. In a gluing machine, a glue containing trough, a glue applying roller within and supported by the trough, a wiping roll within and supported by the trough and arranged relatively to the front of said other roll, driven operating means for said rolls, a pair of superposed guide rolls arranged at the front of the applying roll and above the wiping roll, a platform positioned over the trough forwardly of said applying roll and being formed with depending legs for seating upon the front of the trough, a combined holding-down and guide roll arranged over the top of the applying roll and rearwardly of said superposed rolls, a set of spaced pick-up fingers arranged over the top of the applying roll rearwardly of, opposing and extending in close proximity to the bottom of the rear side of said combined holding-down and guide roll, shiftable supporting means common to and for bodily shifting simultaneously said platform, guide rolls and pick-up fingers to a position rearwardly of said applying roll, said shiftable supporting means being normally seated directly upon the sides of and hinged at its rear end to the rear end of the trough said platform being of a length to extend forwardly beyond the front of the trough when said supporting means is in normal position, spaced parallel holders extending rearwardly from said trough for maintaining said supporting means upright when in shifted position, and tensioning means for said wiping roll connected to the latter and arranged within and supported from the bottom of the trough.

3. In a gluing machine, a glue applying roll, a combined coated material holding down and guide roll arranged over the said other roll, spaced parallel upstanding supports carrying said material holding down and guide roll, a bar mounted in said supports in proximity to their rear ends, a series of spaced parallel horizontally disposed sidewise opposed material pick-up-fingers of blade-like-form disposed on a lengthwise edge

thereof and each gradually increasing in height from its rear to its front end, said bar extending through said fingers in proximity to their rear ends, each of said blades having an upstanding oppositely beveled front end edge inclining rearwardly from its bottom to its top in the same plan throughout, each of said blades having its lower front corner in the form of a point positioned over the said applying roll in proximity to said guide roll and its front edge arranged in close proximity to the guide roll, and a holding down means extending through said blades forwardly over and below said bar and free of connection to said supports.

4. In a gluing machine, a glue containing trough, a glue applying roll within and supported by the trough, a wiping roll within and supported by the trough and arranged relatively to the front of the said other roll, driven operating means for said rolls, a platform positioned over the trough, forwardly of said applying roll, a rotatable combined material feeding and guiding means arranged in juxtaposition to said applying roll, said platform extending to a point in proximity to said second-named means, said second-named means extending above said platform, a combined material holding down and guide roll arranged over the top of said applying roll and rearwardly of said means, a set of spaced parallel pick-up fingers arranged directly over the rear of the top of said applying roll and extending towards and disposed in close proximity to the bottom of the rear side of said combined holding down and guide roll, a normally stationary shiftable supporting structure seating on the trough common to and for normally maintaining said platform, second-named means, guide roll and pick-up fingers, in juxtaposition to said trough and applying roll and for bodily shifting simultaneously said platform, means, guide roll and pick-up fingers, to a position rearwardly of said applying roll, said structure being pivoted to said trough, and spaced holders extending rearwardly from said trough for holding said supporting structure upright when shifted.

JULIUS M. MINKOW.
